CLAIM

The ornamental design for a ventilator for a vehicle,
housing structure or the like, as shown.

DESCRIPTION

FIG. 1 is a front perspective view of a ventilator showing my design;

FIG. 2 is a rear perspective view of the said ventilator;

FIG. 3 is a side elevation of the said ventilator; and

FIG. 4 is an end elevation of the said ventilator.

FIG. 5 is a section taken along line 5—5 in FIG. 3.

FIG. 2FIG. 1
